UNITED STATES PATENT OFFICE

2,562,085

STARTING DEVICE FOR INTERNAL-
COMBUSTION ENGINES

Claud J. Dry and Dale C. Orcutt, Athens, Ohio

Application May 29, 1948, Serial No. 30,095

7 Claims. (Cl. 123—185)

1

This invention relates to a starting device. More particularly, it relates to a manually operable starting device for starting a small internal combustion motor.

Motors such as used on motor scooters and the like present a problem in design and operation of a starting mechanism. Thus, for reasons of economy in manufacture, simplicity of design and weight considerations, an electrical starting system such as used in a passenger automobile is impracticable. Heretofore, it has been the practice to provide a mechanical starter employing a ratchet, light gears, etc., to provide manual means of starting such a motor. Such starters are, however, disadvantageous and, in fact, limit the size of the motor that can be used in a small, lightweight vehicle such as a motor scooter.

It is an object of the present invention to provide an improved form of manually operable starting device for an internal combustion engine.

It is a further object of the invention to provide a starting device for a small, lightweight internal combustion engine which is simple in design and light in weight, yet is effective to impart a high starting speed to a motor shaft.

It is a still further object of the invention to provide a starting device for small internal combustion engines which is manually operable and which is also safe to operate.

These and other objects of the invention will appear from the ensuing description and the appended claims.

One form which the invention may assume is exemplified in the following description and illustrated by way of example in the accompanying drawing, in which:

The figure is a view in side elevation of the starting device of the invention.

Referring now to the drawing, secured to the crank shaft 1 of a motor 2 is a pinion 3 which is rotated by a starting device generally designated as 4. A foot or hand lever 10 having at its free end a convenient handle or foot treadle 11 is provided, and the other end of the lever is rigidly secured to another lever 12 pivoted at 13 to the framework 14 of a vehicle. A coil spring 15 secured at 16 to the framework of the vehicle and at 17 to the lever holds the latter in rearward position as shown. A rack 18 having rack teeth 19 meshing with the teeth of the pinion is also provided, one end of the rack being pivotally secured at 20 to a free linkage 25, the other end of which is pivotally secured at 26 to the rearward end of the lever 12. The lever 12 is

2

provided with a rearwardly extending finger 27, which overlies and abuts the upper surface of the free linkage 25 for a purpose described hereinafter. The other end of the rack 18 is secured to a slide 28 which is slidably received in a guide 29 pivotally secured at 30 to the framework of the vehicle.

In operation, the foot treadle or handle 11 is pushed forwardly, resulting in pivoting the lever 12 in a clockwise direction as viewed in the figure. The rack 18 is thus moved downwardly into meshing relationship with the pinion 3 and is also pulled forwardly, thus causing the pinion to rotate and start the motor. The slide 28 and guide 29 serve to guide the rack in its forward movement and to allow pivotal movement of the same into and out of engagement with the pinion 3. At the end of the forward stroke, the foot treadle or handle 11 is released and the coil spring 15 returns the lever to its original rest position. The finger 27 acting upon the upper surface of the free linkage 25 serves to pivot the rack upwardly and thus to clear the pinion 3 on the return stroke.

It will be seen that there is thus provided a starting device which is of simple design yet is effective in use and which provides several advantages. Thus, the direction of rotation of the motor shaft is the same as the direction of force applied to the foot treadle or handle. Also, the finger 27 and free linkage 25 insure that the rack meshes with the pinion 3 on the down stroke and clears the pinion on the return stroke. The starting device thus described has been successfully used in starting relatively large motors installed on motor scooters and the like.

While we have shown the preferred form of our invention, it is to be understood that various changes may be made in its construction by those skilled in the art without departing from the spirit of the invention as defined in the appended claims.

Having thus described our invention, what we claim and desire to secure by Letters Patent is:

- 45 1. A cranking device of the character described comprising a crankshaft having a pinion fixed thereto, a rack supported for pivotal and longitudinal movement and adapted when in one pivotal position to mesh with said pinion, a lever supported for pivotal movement, and a link pivotally connected to said lever and rack, said link and lever being operable to draw said rack across said pinion and thereby rotate the same.
- 50 2. The device of claim 1, including resilient

means for holding said lever in a predetermined pivotal position.

3. A cranking device of the character described comprising a crankshaft having a pinion fixed thereto, a rack, a pivotally supported guide for said rack, said guide supporting said rack for pivotal and sliding movement, a lever supported for pivotal movement, resilient means holding said lever in a predetermined pivotal position, and a link between said rack and lever, said link being pivotally connected to said rack and to said lever.

4. The device of claim 3, including a finger extending outwardly from the end of said lever which is connected to said link and overlying said link so as to pivot said rack out of engagement with said pinion upon the return stroke thereof.

5. A starting device for an internal combustion engine comprising a rack having teeth adapted to mesh with the teeth of a pinion fixed to the crankshaft of a motor, a pivotally supported guide member supporting one end of said rack for pivotal and sliding movement, a lever supported for pivotal movement, a spring for holding said lever in predetermined pivotal position, a link pivotally connected to said lever and rack, and a finger extending outwardly from and fixed to said lever so as to bear upon said link and thereby normally lift said rack free from its mating pinion.

6. A cranking device comprising a rotatable shaft having a pinion fixed thereto, a rack supported for pivotal and longitudinal movement and capable of engaging said pinion when in one pivotal position, a lever for pivoting said rack and moving it longitudinally, a link pivotally connected to said lever and rack, and resilient means for returning said lever to starting position.

7. A cranking device comprising a rotatable shaft having a pinion fixed thereto, a rack supported for pivotal and longitudinal movement and capable of engaging said pinion when in one pivotal position, a lever, a link pivotally connected to adjacent ends of said rack and lever, a finger extending outwardly from said lever and overlying said link so as normally to urge said rack out of engagement with said pinion, and resilient means normally holding said lever in rearward, disengaged position.
